(57) **CLAIM**

The ornamental design for a tip of a hexagon wrench, as shown and described.

DESCRIPTION

FIG. 1 is a front view of a tip of a hexagon wrench showing my new design;

FIG. 2 is a rear view thereof;

FIG. 3 is a left side elevation view thereof;

FIG. 4 is a right side elevation view thereof;

FIG. 5 is a plan view thereof;

FIG. 6 is a bottom view thereof;

FIG. 7 is a cross-sectional view of a cut section thereof cut along line A—A of FIG. 1;

FIG. 8 is a cross-sectional view of a cut section thereof cut along line B—B of FIG. 1; and,

FIG. 9 shows a usage state thereof.

The broken lines showing the remainder of the hexagon wrench and the environment thereof is for illustrative purposes only and forms no part of the claim.

Portions of the tip of a hexagon wrench are wrenched off when a torque to tighten a screw is too high.
